UNITED STATES PATENT OFFICE.

RONALD V. GRAHAM, OF NEW YORK, N. Y.

CAN SPOUT.

Application filed November 22, 1923. Serial No. 676,388.

To all whom it may concern:

Be it known that I, RONALD V. GRAHAM, a citizen of the United States of America, and a resident of the city of New York, 5 borough of the Bronx, in the county of Bronx and State of New York, have invented a new and Improved Can Spout, of which the following is a description.

My invention relates to a spout for pouring the contents of a can and more particularly relates to a can spout having means to puncture the can and position the spout for pouring.

The general object of my invention is to 15 provide a can spout of the indicated type improved with respect to the puncturing means and means for causing the spout to be seated tightly on the can to prevent leakage.

20 The nature of the invention and its distinguishing features and advantages will clearly appear as the description proceeds.

Reference is to be had to the accompanying drawings forming a part of this specification, it being understood that the drawings are merely illustrative of one example 25 of the invention.

Figure 1 is a side elevation of a can spout 30 embodying my invention showing the same in position on a can shown partly in vertical section;

Figure 2 is a top plan view of the spout in position on the can;

Figure 3 is an inverted plan view with the 35 spout in section as indicated by the line 3—3, Figure 1;

Figure 4 is a perspective view of the can spout.

In carrying out my invention in accordance 40 with the illustrated example the spout is made with a tubular cylindrical body 10, the inner edge being in the form of a puncturing member 11. Adjacent the base of the puncturing member 11 is a lateral 45 annular flange 12 for bearing against a can top A or against an interposed packing washer 15. The puncturing device 11 is cut away at a side thereof and the defining side edge 13 is such as to produce a rounded 50 front cutting end 14 on said puncturing member.

In order to cause the can spout to be drawn firmly into position with the flange 12 pressed tightly against the can top A or against the washer 15, I form the spout with an oblique slot 16 at the base of the puncturing member 11. Said slot follows the lateral curvature of the puncturing device 11 and it tapers toward the inner end 17.

With the above-described construction the spout is forced into the can top A, the puncturing member 11 cutting its own way. The entrance of the can spout forms on the can top A a burr or flange a at one side 65 of the opening formed in the can top by the insertion of the spout. After the puncturing member 11 has passed through the can top, the spout is turned about its own axis to cause a side edge 18 of the puncturing member 11 to press against and bend backward the flange a on the can top. The turning movement of the spout jams the flange a into a form returned upon itself 70 and forces it into the narrowed end 17 of slot 16, the can spout thereby exerting a cam action against the bent flange a thus drawing the spout inwardly, the flange 12 finally being pressed home to prevent leakage.

I would state in conclusion that while the illustrated example constitutes a practical embodiment of my invention, I do not limit myself strictly to the exact details herein illustrated, since, manifestly, the same can 85 be considerably varied without departure from the spirit of the invention as defined in the appended claim.

Having thus described my invention, I claim:

A can spout having a body, a laterally directed flange on said body, and a tubular puncturing device on the spout in front of said flange, said puncturing device being cut away at a side thereof and having a bevelled cutting edge at the front end and a lateral cam slot adjacent the base of the puncturing device opening into the space formed by the cutaway portion, said slot tapering toward its inner end.

RONALD V. GRAHAM.
